CROWN GRINDER

Mark I. Rudnicki, Harper Woods, and Wilhelm Dralle, Detroit, Mich., assignors, by mesne assignments, to Ex-Cell-O Corporation, Detroit, Mich., a corporation of Michigan

Filed May 5, 1958, Ser. No. 732,974

14 Claims. (Cl. 51—33)

This invention relates to grinding machines.

One object of this invention is to provide a grinding machine adapted to form a crown tooth gear.

Another object of the invention is to provide a grinding machine having a grinding wheel which oscillates on a preset crown radius relative to the work.

A further object of the invention is to provide a grinding machine having means for dressing the grinding wheel which automatically compensates for the diminishing diameter thereof so that the wheel is always grinding on the same preset crown radius.

Other objects and features of the invention will become apparent as the description proceeds, especially when taken in conjunction with the accompanying drawings, illustrating a preferred embodiment of the invention, wherein:

Fig. 1 is a front elevational view of a grinding machine embodying the invention.

Fig. 2 is a view taken on the line 2—2 of Fig. 1.

Fig. 3 is a sectional view taken on the line 3—3 of Fig. 1.

Fig. 4 is a diagrammatic view of the motor for oscillating the grinding wheel.

Fig. 5 is a view partly in section of the down feed mechanism.

Fig. 6 is a diagrammatic view illustrating the hydraulic operating system.

Fig. 7 is a sectional view taken on the line 7—7 of Fig. 6, illustrating the locking valve for the hydraulic operating mechanism.

Fig. 8 is a wiring diagram.

Referring now more particularly to the drawings, the machine comprises a bed 10 on which is supported a reciprocable table 12. A work support is mounted on the table, including a head stock 14 and a tail stock 16 having centers 18 for engaging an arbor on which the gear G to be ground is mounted. There is also an indexing mechanism (not shown) for periodically rotating the arbor step by step. A grinding wheel dresser 20 is mounted on the table.

A pair of columns 22 and 24 extend upwardly from the bed at the rear of the table, and the adjacent surfaces of the columns are spaced apart and define parallel vertical guiding surfaces 26. A support block 28 is located between the columns 22 and 24 and guided for vertical reciprocation by the guiding surfaces 26. A shaft 30 extends horizontally and at right angles to the path of movement of table 12, and is journaled for rotation in the support block by bearings 32. A generally vertical arm 34 is carried by the shaft 30 to oscillate as a unit therewith. The arm 34 has a transverse flange 36 formed with a recess 37 for receiving the flange 38 on the end of shaft 30. The flange is secured within the recess by fasteners 40.

The arm 34 has a longitudinally extending dovetail track 42. A motor mount 44 is formed with a recess receiving the dovetail track to permit sliding movement

2

of the motor mount lengthwise along the arm. A motor 46 is carried by the mount and drives a spindle 48 on which is mounted the formed grinding wheel 50. The motor is oriented with its shaft 48 extending parallel to shaft 30 and at right angles to the path of movement of the table.

The arm 34 carries a longitudinally extending elongated screw 52 which is mounted on the arm for free rotation by the handle 54 at the upper end but which is held against longitudinal movement relative to the arm. The screw engages a nut 55 secured to the motor mount so that rotation of the screw will result in movement of the motor mount lengthwise relative to the arm 34. An automatic dress feed device 56 is secured to the lower end of the arm and is operatively connected to the screw 52. This invention is not concerned with the automatic dress feed device and therefore it will not be described in detail. The automatic dress feed provides a means for automatically rotating the screw 52 to move the grinding wheel during the dressing operation.

The shaft 30 is oscillated by an oscillating motor 60 mounted on a bracket 62 carried by the support 28. The motor is diagrammatically illustrated in Fig. 4 and comprises the housing 64 supporting therewithin a shaft 66 for rotation. The shaft 66 has secured to it a vane 68 adapted to oscillate within the arcuate fluid chamber 70. When fluid under pressure is alternately admitted to opposite ends of this chamber through ports 72 and 74 via lines 76 and 78, the vane 68 and shaft are oscillated back and forth. Hydraulic fluid under pressure is alternately admitted to lines 76 and 78 by the 4-way valve 80 from a hydraulic line 82. The lines 76 and 78 are alternately exhausted by the valve through exhaust line 84. The valve is controlled by solenoids 86 and 88. Motor shaft 66 is secured to shaft 30 by coupling 87.

The mechanism for vertically moving the shaft support 28 comprises a screw threaded rod 90 and a nut 92 on the shaft support threadedly receiving the rod. The rod is supported at its upper and lower ends for rotation and vertical or axial reciprocation. At its upper end as shown in Fig. 5, the rod has a splined section which is splined to a sleeve 94 so that the rod and sleeve rotate as a unit but may move axially relative to one another. The sleeve is held against axial movement by the frame structure 101. A bevel gear 100 is secured to the sleeve and meshes with a bevel gear 102 carried by a shaft 104 which is operated by a handle 106 for the manual rotation of the rod 90. Thus the handle 106 may be employed to shift the shaft support 28 vertically. This mechanism may be used not only for the initial adjustment of the grinding wheel into operative relation to the work (gear G) but also for manually feeding the grinding wheel step by step. Where it is so used, the screw threaded rod 90 is held against axial movement and consequently will impart movement to the shaft support 28 by its rotation in the nut 92.

However, in the automatic feed the rod 90 is moved axially by a mechanism now to be described. The rod 90 at its upper end is supported for axial as well as rotary movement. Its lower end is similarly journaled in the bed of the machine. The automatic feed mechanism is indicated generally at 112 and includes a member 114 which is swiveled upon the rod 90 by end thrust roller bearings 116 and 118. These bearings prevent any relative axial movement between the rod 90 and the member 114 while permitting free relative rotation. The member 114 is axially slidable within a cylindrical bearing 120 in the housing 122 and is provided centrally with a portion 124 which is connected by a wrist pin 126 with a forked connecting rod member 128. The upper portion of the member 128 is apertured for the passage

therethrough of a horizontal shaft 130 which is suitably journaled for rotation within the housing 122. The shaft 130 has an eccentric portion 132 on which the member 128 is mounted. Thus the rotation of the shaft 130 in the housing 122 will through the eccentric 132 and connecting rod member 128 impart an axial movement to the member 114 and shaft 90. Beyond the eccentric 132 the shaft 130 has a concentric portion on which is mounted a pinion 136. The pinion is in mesh with a rack member 138 which has on opposite ends thereof piston portions 140 and 142 engaging in hydraulic cylinders 144 and 146 which are mounted on opposite sides of the housing 122 by bolts 148.

Before further description of the apparatus, it may be stated that the feeding movement of the grinding wheel is effected by an axial movement of the screw threaded rod 90 which, in turn, is accomplished by a rotation of the shaft 130 causing the eccentric portion 132 thereof to move the connecting rod member 128 and member 114. The rotation of the shaft 130 is accomplished by a movement of the pistons 140 and 142, which movement is controlled by admission of hydraulic fluid to one of the cylinders and expulsion of fluid from the other cylinder. Consequently, the amount of feeding movement must be controlled by accurately metering the fluid entering and leaving the cylinders 144 and 146.

Generally described, the hydraulic operating system includes a source of hydraulic fluid under pressure, a valve controlling the admission of fluid alternately to the cylinders 144 and 146, a metering means connected to the cylinder 144 operating to successively eject predetermined volumes of fluid therefrom under pressure of the fluid admitted to the other cylinder, and a valve controlling the successive operations of the metering means. More specifically, the system includes a tank 150 for the fluid, a pump 152 operated by an electric motor 154 for propelling the fluid from the tank through an outgoing conduit 156 and a relief valve 158 which returns the unused fluid to the tank while maintaining a predetermined constant pressure on the line 156. The line 156 has a branch 160 extending to the cylinder 146 and a second branch 162 leading to the metering device 164. In the line 156 is an electromagnetically operated valve 166 and in the branch 162, an electromagnetically operated valve 168. A conduit 170 extends from the cylinder 144 to the metering device and in this conduit is a normally closed and locked check valve 172. The valve 166 normally opens the conduit 156 to maintain hydraulic pressure on the fluid in the cylinder 146 but in another position of this valve, fluid is exhausted from the cylinder 146 to be returned to the tank 150 while pressure fluid is supplied through a conduit 174 to the cylinder 144. A check valve 176 in this conduit prevents movement therethrough in the opposite direction. The valve 168 normally opens the branch conduit 162 to supply fluid through a portion 178 thereof to one end of the cylinder of the metering device 164 (as will be hereinafter explained), while in another position of the valve 168, the conduit portion 178 will be connected to an exhaust conduit 180 returning fluid to the tank. In the latter position of the valve 168, the branch conduit 162 is connected to a conduit 182 leading to the check valve 172 and functioning to unlock and open the valve. There is also a conduit 184 leading from the conduit portion 170 to the conduit 182 but containing a check valve 186 which prevents movement of fluid therethrough in the reverse direction. In the normal position of the valve 168, both the conduits 182 and 184 are connected with the exhaust conduit 180.

The metering device 164 comprises a cylinder 188 containing a free piston 190, the amplitude of movement of which is limited by an adjustable stop 192. The conduit 170 connects with the end of the cylinder containing the stop 192, while the conduit 178 is connected to the opposite end of the cylinder. Thus normally pressure fluid

in the conduits 162 and 174 holds the piston 190 against the stop 192.

5 The check valve 172 has a spring 194 for normally holding the valve element 196 seated as illustrated in Fig. 7. There is however a piston 198 in a cylinder 200 connected to the conduit 182 and this piston when actuated will press a rod 202 against the valve element to unseat the same.

10 The operation of the hydraulic system as thus far described is as follows: Fluid under pressure fills both of the cylinders 144 and 146 to press against pistons 142 and 144 therein and hold the rack member 138 against movement. This stationary position of the parts is assured as the check valve 172 is locked from opening which prevents any escape of fluid from the cylinder 144, while the cylinder 146 is in open communication with the conduit 156 containing the pressure fluid. Assuming that the valve 168 is operated, the valve 166 remaining in normal position, this will first connect the conduit 162 with the conduit 182 thereby unseating the check valve 172. Also, the conduit 178 will be connected to the exhaust conduit 180. Consequently, the piston 190 is free to move in the cylinder 188 under pressure of fluid expelled from the cylinder 144 and passing into the 15 metering device through the conduit 170 and open check valve 172. Such expulsion from the cylinder 144 is caused by the pressure of fluid in the cylinder 146 which actuates the pistons 142 and 144 and moves the rack 138 a corresponding distance. If the valve 168 is then restored to normal position, the valve 172 will be closed and locked and pressure fluid will enter the metering cylinder 188 through the conduit 178 returning the piston 190 to its position against the stop 192 and expelling fluid from the opposite side of said piston through the conduit 184 and check valve 186 into the exhaust conduit 180.

20 It is therefore apparent that each actuation of the valve 168 will result in the expulsion of a measured volume of fluid from the cylinder 144 and a corresponding movement of the pistons 142 and 144 and rack 138. The 25 rack will actuate the pinion 136 which will rotate the shaft 130 causing the eccentric 132 and connecting rod member 128 to lower the member 114 and screw threaded rod 90. This will feed the grinding wheel into the work a predetermined amount, and in successive operations of the valve 168 the grinding wheel will be fed step by step to a predetermined limit. The valve 166 will then be 30 operated (through control means hereinafter described) which will connect the cylinder 144 with the pressure line 156 and the cylinder 146 with the exhaust line thereby 35 returning the rack 138 and the mechanism connected therewith to normal position.

40 In operation, and with a gear mounted on an arbor carried by centers 18, the grinding wheel will be oscillated back and forth across the gear through an interdental space of the gear to fashion the teeth on opposite sides thereof to the contour of the formed grinding wheel. The crown radius ground on the gear teeth will equal the 45 distance between the axis of rotation of the oscillating shaft 30 and the periphery of the grinding wheel indicated by the dimension line 220. The grinding wheel is oscillated by the shaft 30 and supporting arm 24 to opposite sides of a vertical position sufficiently to clear the gear at either limit. At each limit of oscillation of the grinding wheel, the shaft support 28 is indexed downwardly 50 a small increment to feed the wheel into the work step by step.

55 Referring to Figs. 4 and 8, the oscillation of the shaft 30 and grinding wheel is started by closing the manual pushbutton 222 energizing relay CR and closing contacts CR1 and CR2 to seal in the relay and send current to the circuits 224 and 226. These circuits contain the solenoids 86 and 88 which shift the valve 80 60 between its two positions. When the shaft 66 of the oscillating motor 60 swings to the limit illustrated in Fig. 4, its vane engages limit switch 228 to energize solenoid 86

sending pressure fluid through line 76 and exhausting line 78 to swing the shaft 66 and its vane 68 to the other limit engaging limit switch 230. This reverses the fluid flow, sending fluid under pressure through line 78 and exhausting line 76 to produce a continuous oscillation of the grinding wheel about the axis of shaft 30.

Limit switch 232 is closed at the same time that limit switch 228 is closed energizing the solenoid 234 of the electromagnetically operated valve 168 resulting in operation of the down feed mechanism to move the screw threaded rod 90 down a step and correspondingly moving the shaft support 28 to feed the grinding wheel into the work. Limit switch 236 is closed at the same time limit switch 230 is closed, likewise actuating the valve 168. Hence the grinding wheel is fed downwardly step by step at each limit of oscillation of the grinding wheel.

When the shaft support reaches a predetermined lower limit of movement, it engages a limit switch 240 opening the switch to de-energize relay CR and open its contacts to de-energize the down feed mechanism and oscillating mechanism of the motor 60. Limit switch 240 has a second contact 241 which simultaneously closes to energize relay 242 of the electromagnetically operated valve 166. This relay has a contact 243 for sealing in the circuit. As previously described, the operation of valve 166 will connect the cylinder 144 with the pressure line 156 and the cylinder 146 with the exhaust, thereby actuating the rack 138 in the reverse direction rotating the shaft 130 to its initial position and returning the shaft support 28 to its upper limit in which the grinding wheel is raised clear of the work. At its upper limit, the shaft support opens limit switch 246 to de-energize relay 242.

After the foregoing cycle of operation, the table 12 may be actuated to move the gear C clear of the grinding wheel and to bring the grinding wheel dresser 20 under the grinding wheel. The grinding wheel may then be fed downwardly into the dresser mechanism either by the automatic dress feed 56 or by the manual rotation of the screw 52 by the handle 54. Since the dresser is fixed in relation to the table, it will grind the peripheral contour of the grinding wheel without disturbing the crown radius dimension 220 between the periphery of the wheel and the axis of rotation of shaft 30. Hence the diminishing diameter of the grinding wheel is automatically compensated for by this method of dressing, and the grinding wheel will continue to grind on the same radius in succeeding cycles.

After dressing, the table is returned to the illustrated position, the gear G is indexed to bring the next interdental space in register with the grinding wheel, and the wheel may be initially moved down into operative relation to the gear G by the manual rotation of the screw threaded rod 90 by handle 106. Thereafter the manual pushbutton 222 is closed to initiate the automatic down feed.

What we claim as our invention is:

1. In a grinding machine, a support, an arm rotatably carried by said support, a rotatable grinding wheel carried by said arm in spaced relation to the axis of rotation of said arm, means for oscillating said arm about its axis of rotation, and means for automatically moving said support in a direction transverse to said axis between separate oscillations of said arm to feed said grinding wheel into a workpiece.

2. In a grinding machine, a support, means for guiding said support for movement in opposite directions, a shaft rotatably carried by said support having its axis extending transversely of the path of movement of said support, an arm extending radially from said shaft and secured thereto for rotation as a unit therewith, a rotatable grinding wheel carried by said arm in spaced relation to the axis of rotation of said shaft and with its axis of rotation parallel to that of said shaft, means for oscillating said shaft, and automatic means for moving said

support in one direction between separate oscillations of said shaft to feed grinding wheel into a workpiece.

3. A machine as in claim 2, including means for adjusting said grinding wheel on said arm toward and away from the axis of rotation of said arm.

4. In a grinding machine, a support, means for guiding said support for vertical movement in opposite directions, a horizontal shaft rotatably carried by said support, an arm fixed to said shaft and extending radially therefrom in a generally upward direction, a rotatable grinding wheel carried by said arm in spaced relation above the axis of rotation of said shaft, means for oscillating said axis of rotation of said shaft and with its axis of rotation parallel to that of said shaft, means for oscillating said opposite sides of a vertical position, and means for moving said support downwardly during oscillation of said shaft to feed said grinding wheel into a workpiece.

5. In a grinding machine, a support, means for guiding said support for vertical movement in opposite directions, 20 a horizontal shaft rotatably carried by said support, an arm fixed to said shaft and extending radially therefrom in a generally upward direction, a rotatable grinding wheel carried by said arm in spaced relation above the axis of rotation of said shaft and with its axis of rotation parallel to that of said shaft, means for oscillating said 25 shaft to move said arm between limiting positions at opposite sides of a vertical position, and means for moving said support downwardly when said arm is in a limiting position due to oscillation of said shaft to feed said grinding wheel into a workpiece.

6. In a grinding machine, a support, means for guiding said support for vertical movement in opposite directions, a horizontal shaft rotatably carried by said support, an arm fixed to said shaft and extending radially therefrom in a generally upward direction, a rotatable grinding wheel carried by said arm in spaced relation above the axis of rotation of said shaft and with its axis of rotation parallel to that of said shaft, means for oscillating said shaft to move said arm between limiting positions at opposite sides of a vertical position, and means for successively moving said support downwardly at each limiting position in the oscillation of said shaft to feed said grinding wheel into a workpiece.

7. In a grinding machine, a support, means for guiding 45 said support for vertical movement in opposite directions, a horizontal shaft rotatably carried by said support, an arm fixed to said shaft and extending radially therefrom in a generally upward direction, a rotatable grinding wheel carried by said arm in spaced relation 50 above the axis of rotation of said shaft and with its axis of rotation parallel to that of said shaft, means for oscillating said shaft to move said arm between limiting positions at opposite sides of a vertical position, and means responsive to movement of said arm for successively moving 55 said support downwardly at each limiting position in the oscillation of said shaft to feed said grinding wheel into a workpiece.

8. A machine as in claim 7, including means for adjusting said grinding wheel on said arm toward and away 60 from the axis of rotation of said arm to vary the radius of oscillation of said wheel.

9. In a grinding machine, a bed, a reciprocable table mounted on said bed, a work support mounted on said table including a head stock and a tail stock, a center 65 in each of said head stock and tail stock, an arbor for mounting a workpiece held by said centers, a pair of columns extending upwardly from said bed in spaced relation to said table, a support block located between said columns and guided thereby during vertical movement 70 therebetween, manually operable means associated with said support block to provide vertical movement thereof in opposite directions between said columns, a horizontal shaft extending in a transverse direction with respect to said arbor and rotatably carried by said support, an arm 75 fixed to said shaft at the end thereof adjacent said table

and extending radially therefrom in a generally upward direction, a motor mounted on said arm for vertical sliding movement therealong, means for producing sliding movement of said motor along said arm, a spindle secured to and driven by said motor, a grinding wheel mounted on said spindle in spaced relation above the axis of rotation of said shaft and with its axis of rotation parallel to that of said shaft, hydraulic means for automatically oscillating said arm about the axis of rotation of said shaft between limiting positions at opposite sides of a vertical position, and hydraulic means responsive to the oscillation of said arm for automatically moving said support downward a predetermined amount between said columns on said arm reaching each limiting position in the oscillation thereof to feed said grinding wheel into a workpiece positioned on said arbor while maintaining the radial dimension between the shaft and spindle so that a crown having a predetermined surface contour will be formed on said workpiece.

10. In a grinding machine, a bed, a work support mounted on said bed, guide means mounted on said bed in spaced relation to said work support, a support block positioned adjacent said guide means for guided movement therealong, a horizontal shaft extending in a transverse direction with respect to said work support and rotatably carried by said support block, an arm fixed to said shaft extending radially therefrom in a generally upward direction, a rotatable grinding wheel mounted on said arm in spaced relation above the axis of rotation of said shaft and with its axis of rotation parallel to that of said shaft, means for automatically oscillating said arm about the axis of rotation of said shaft between limiting positions at opposite sides of a vertical position, and means responsive to the oscillation of said arm for automatically moving said support block downward a predetermined amount on said arm reaching each limiting position in the oscillation thereof to feed said grinding wheel into a workpiece positioned on said work support while maintaining the radial dimension between the shaft and grinding wheel so that a crown having a predetermined surface contour will be formed on said workpiece.

11. In a grinding machine, a bed, a work support mounted on said bed, guide means mounted on said bed in spaced relation to said work support, a support block positioned adjacent said guide means for guided vertical movement therealong, manually operable means associated with said support block to provide vertical movement thereof in opposite directions, a horizontal shaft extending in a transverse direction with respect to said work support and rotatably carried by said support block, an arm fixed to said shaft at the end thereof adjacent said work support extending radially therefrom in a generally upward direction, a rotatable grinding wheel mounted on said arm in spaced relation above the axis of rotation of said shaft and with its axis of rotation parallel to that of said shaft, means for automatically oscillating said arm about the axis of rotation of said shaft between limiting positions at opposite sides of a vertical position, and means responsive to the oscillation of said arm for automatically moving said support block downward a predetermined amount on said arm reaching each limiting position in the oscillation thereof to feed said grinding wheel into a workpiece while maintaining the dimension between the grinding wheel and axis of oscillation thereof so that a crown having a predetermined surface contour will be formed on said workpiece.

5 8
terminated amount on said arm reaching each limiting position in the oscillation thereof to feed said grinding wheel into a workpiece positioned on said work support while maintaining the radial dimension between the shaft and grinding wheel so that a crown having a predetermined surface contour will be formed on said workpiece.

10 12. In a grinding machine, a bed, a work support mounted on said bed, guide means mounted on said bed in spaced relation to said work support, a support block positioned adjacent said guide means for guided movement therealong, a horizontal shaft extending in a transverse direction with respect to said work support and rotatably carried by said support block, an arm fixed to said shaft extending radially therefrom in a generally upward direction, a motor mounted on said arm for vertical sliding movement therealong, means for producing sliding movement of said motor along said arm, a spindle secured to and driven by said motor, a rotatable grinding wheel mounted on said spindle in spaced relation above the axis of rotation of said shaft and with its axis of rotation parallel to that of said shaft, means for automatically oscillating said arm about the axis of rotation of said shaft between limiting positions at opposite sides of a vertical position, and means responsive to the oscillation of said arm for automatically moving said support block downward a predetermined amount on said arm reaching each limiting position in the oscillation thereof to feed said grinding wheel into a workpiece positioned on said work support while maintaining the radial dimension between the shaft and grinding wheel so that a crown having a predetermined surface contour will be formed on said workpiece.

15 13. Guide means, a support positioned adjacent said guide means for guided movement therealong, a rotatable grinding wheel carried by said support, means for oscillating said grinding wheel about an axis parallel to the axis of rotation thereof, and automatic means for moving said support along said guide means between separate oscillations of said grinding wheel.

20 14. Guide means, a support positioned adjacent said guide means for guided movement therealong, a rotatable grinding wheel carried by said support, means for oscillating said grinding wheel about an axis parallel to the axis of rotation thereof, and means responsive to oscillation of said grinding wheel for automatically moving said support a predetermined amount on said grinding wheel reaching each limiting position in the oscillation thereof to feed said grinding wheel into a workpiece while maintaining the dimension between the grinding wheel and axis of oscillation thereof so that a crown having a predetermined surface contour will be formed on said workpiece.
